(57) **CLAIM**

The ornamental design for spectacles, as shown and described.

DESCRIPTION

FIG. 1.1 is a front elevation view of spectacles showing our new design;

FIG. 1.2 is a top plan view thereof;

FIG. 1.3 is a right side elevation view thereof, the left side elevation view being a mirror image of the right side elevation view;

FIG. 1.4 is a front, left bottom perspective view thereof; FIG. 1.5 is a front, left top perspective view thereof; and FIG. 1.6 is another front, left bottom perspective view thereof, with the bridge element being detached from the spectacles.

The broken lines depict portions of the spectacles that form no part of the claimed design.
